UNITED STATES PATENT OFFICE.

EDWARD JOHNSON, OF EAST ORANGE, NEW JERSEY, ASSIGNOR TO MEINECKE & COMPANY, OF NEW YORK, N. Y., A CORPORATION OF NEW JERSEY.

SPUTUM-CUP HOLDER.

Application filed June 4, 1923. Serial No. 643,187.

To all whom it may concern:

Be it known that I, EDWARD JOHNSON, a citizen of the United States, residing at East Orange, in the county of Essex and State of New Jersey, have invented new and useful Improvements in Sputum-Cup Holders, of which the following is a specification.

This invention relates essentially to a holder preferably made of metal for paper sputum cups in which the swingingly mounted cover or lid of the holder actuates a device to completely cover the hinge joint so that it will be impossible for a person to accidentally spit on the hinge.

An object of the invention is to provide the cover with means for attaching to it a portion or flap of the rear side of the paper sputum cup, whereby when the cover is raised the rear flap of the cup follows it to entirely cover the hinge joint.

Another object of the invention is to slidably connect the flap to the cover so that the cup can be lifted out by merely pushing it upward by pressing on the bottom thus preventing any of the sputum on the exterior part of the flap or in the holder from getting in contact with the fingers.

At present it is the custom to use a holder having a cover made to close automatically by means of a spring, thus keeping from view the contents of the paper sputum cup arranged in the holder.

The great objection to this holder is the fact that the patient not infrequently spits on the exposed hinge when the cover of the holder is raised, making the holder unsightly and unsanitary. While the paper cup can be taken out and burned the holder must be cleaned and sterilized and the cleaning of the hinge is a difficult and disagreeable task.

The present invention resides more particularly in the novel combinations hereinafter described and claimed, reference being made to the accompanying drawing in which:

Fig. 1 represents a perspective view of a holder and cup embodying this invention showing the cover raised.

Fig. 2 is vertical section showing the cover closed.

Fig. 3 is a plan view of the paper blank from which the sputum cup is made.

Fig. 4 is an inverted plan view of the holder.

In the drawing is shown a holder 5 preferably made of thin lacquered tin or suitable material and provided with a cover or lid 6 swingingly mounted at 7 to the rear upper end of the holder 5. A spring 8 coiled about the pivot of the lid normally keeps it closed. The back of the holder is equipped with a handle 9, and a finger member 10 extending from the rear edge of the cover provides means for conveniently opening the cover to afford access to the interior of the holder.

In the holder is arranged a paper sputum cup constructed from a blank 11 having inclined top members or flaps 12 to form a truncated mouth or opening of the sputum cup. These flaps 12 are made integral with the blank 11 and are flexible. When the blank 11 is folded into the form shown in Fig. 1 one of the flaps 13 situated at the rear of the holder is inserted through a slot 14 in the metal lid 6. The result is that this rear flap 13 covers the coiled spring 8 and it is impossible for any sputum to lodge on the spring. The box 5 is open at the bottom and the opening is divided substantially in half by a metal strip 15 which preferably is made integral with and is a continuation of the handle 9. By reason of the member 15 the bottom of the holder has two blank spaces 16 somewhat wider than the width of a person's fingers. As is well-known the paper sputum cup, as soon as it is filled or partly filled, is removed from the holder and burned in an incinerator or otherwise destroyed.

By the construction of my form of holder it is apparent that the sputum cup when it becomes necessary to destroy it can be ejected and removed from the holder if desired by the operation of only one hand and without any possibility of the fingers of the operator becoming soiled by contact with the sputum. This is accomplished in the following manner: The rear flap 13 of the cup 11 which extends through the slot 14 of the cover 6 can be easily pushed through the slot 14 which is slightly longer than the width of the flap 13; the finger member 10 on the top of the lid 6 is then pressed down with the thumb while the finger of the operator is passed through the handle 9 and two

fingers can be placed in the opening 16 on the bottom of the holder and the cup readily ejected.

No claim is made to the form of the paper blank 11. This is an old and well-known form. No claim is made to the opening in the bottom of the holder. Such openings are also old and well-known. My invention consists in so arranging a slot or opening in the cover of the holder that it coacts with and controls one of the rear flap members of the old and well-known type of sputum cup in such manner that the spring of the holder is absolutely protected from any contact with the hinge of the holder, and at the same time the cup can be readily removed from the holder with one hand and without the possibility of the operator having his or her fingers come in contact with the sputum.

I claim:

1. A holder, adapted to contain a sputum cup, a hinged lid on the holder and a transverse slot in the lid, and near the center thereof, to movably coact with the flap of a sputum cup.

2. A sputum cup holder having a swinging lid, a slot in the lid, a sputum cup arranged in the holder, and a flap extending from the back of the cup to slidingly engage the slot.

3. A sputum cup holder having a hinged lid with a slot, a sputum cup arranged in the holder, and a flap extending from the back of the cup made to slidingly engage the slot and to swing with the lid for shielding the hinged joint.

4. The combination with a sputum cup holder having a swinging lid with a slot in the lid, and a sputum cup folded from a substantially circular blank having four flaps extending from the blank, one of the said flaps extending through the slot in the lid of the box and covering the spring.

In testimony whereof I have hereunto set my hand in the presence of two subscribing witnesses.

EDWARD JOHNSON.
